METHOD FOR DRYING SOLIDS

Original Filed June 25, 1929

FIG. 1

INVENTOR.
Rolland D. Myers

BY
Millard F. Peake, Jr
ATTORNEY.

UNITED STATES PATENT OFFICE

1,966,456

METHOD FOR DRYING SOLIDS

Rolland D. Myers, Edgewood Arsenal, Md.

Original application June 25, 1929, Serial No. 373,674. Divided and this application August 2, 1932, Serial No. 627,246

15 Claims. (Cl. 260—162)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates in general to removing contained liquids from volatile solids having a low intersolubility therewith in the liquid phase, and more particularly has reference to a process and apparatus for drying hexachlorethane.

10 Previous to this time, the various methods employed for removing contained liquids from materials of this character have not usually proved well suited for practical purposes. In the past, it has been customary in drying solids, 15 of the type of hexachlorethane for example, to centrifuge the wet material to reduce the moisture content to as low a degree as practical.

The remaining traces of water have been removed to the greatest possible extent by bringing the material in contact with relatively dry air. In carrying on an air-drying operation of this type, however, a large percentage of the solid under treatment is lost, ranging in many instances from an approximate of around ten to 25 over fifteen percent.

An object of this invention is to provide a process and apparatus for removing contained liquids from volatile solids having a low intersolubility therewith in the liquid phase without 30 any appreciable loss of the normally solid material.

Another object of this invention is to provide a process and apparatus for removing contained liquids from volatile solids having a low intersolubility therewith in the liquid phase without any appreciable loss of the normally solid material in which the contained liquid is separated and removed.

Still another object of this invention is to provide a process and apparatus for removing contained liquids from volatile solids having a low intersolubility therewith in the liquid phase without any appreciable loss of the normally solid material in which the solid is separated 45 in the liquid phase and removed.

A further object of this invention is to provide a process of drying hexachlorethane without any appreciable loss of the material.

This invention contemplates in general removing contained liquids from volatile solids having a low intersolubility therewith in the liquid phase by liquefying the solid in a closed vessel and effecting a separation of the liquid layers so as to obtain a product substantially free from 55 moisture.

With these and other objects in view which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions which for the purpose of explanation have been made the subject of illustration.

This application is a division of my application for Method and apparatus for drying hexachlorethane, Serial Number 373,674, filed June 25, 1929.

75 Figure 1 is a sectional view of one form of apparatus in which the contained liquid may be decanted and the normally solid material drawn off in the liquid phase.

80 Referring by numerals to the drawing, there is shown one form of apparatus suitable for carrying on the process of this invention which will be described with reference to one specific application of the invention for the drying of hexachlorethane. This apparatus comprises a 85 plurality of superimposed containers 35 and 36 having jackets 37 and 38 formed integral therewith as shown. The lower jacket is provided with an outlet 39 at the bottom and an inlet 41 at the top, and jacket 38 is likewise provided 90 with a bottom outlet 42 and a top inlet 43.

A member 44 formed of a bowl shaped plate 45 backed against a bowl shaped plate 46 and having a central aperture 47, is interposed between the containers so that it acts as a bottom 95 closure for the upper container 36 and a top closure for the lower container 35. The member 44 is provided in addition with an outer jacket 48 having a plurality of outlets 49 and 51 therein.

100 The lower container 35 is provided with a bottom closure 52 having a conduit 53 formed on one side thereof, adapted to receive an outlet line. The upper container 36 is provided with a dome shaped closure 54 having a central aperture through which is inserted a rod 55. A centrally located tubular extension 56 having an outwardly flanged top 57 is formed on the closure 54. A stuffing gland 58 is adapted to be inserted over the rod 55 and seated in the tubu- 110

lar extension 56, which is provided with packing 59. A tapered extension 61 formed integral with the stuffing gland having a centrally threaded aperture is mounted on the top of the 5 stuffing gland adapted to be engaged by threads 62 formed on the end of rod 55.

It will be noted that the rod 55 extends 10 through the central aperture 47 in the member 44. A plug 63 composed of any suitable material not affected by the substances charged into 15 the containers is mounted on the end of the rod and held by a nut 64. A wheel 65 is fixed on the upper end of the rod 55 so that by rotating the same communication between the two containers may be stopped by the plug 63 stopping 20 the aperture 47.

The dome cover 54 is provided in addition 25 with an upwardly extending tubular extension 66 having a flanged top 67, through which material for treatment is charged, and provided with a closure 68 preferably slidably secured thereon by a bolt 69. In the preferred construction, it will be noted that the closure 68 may be held in the opposite side by insertion in a groove provided 30 in the side of the extension 56. It will be apparent, however, that the closure 68 may be fixed over the opening in any other suitable manner so that it may be conveniently removed and replaced.

35 The jacket 38 on the upper container is connected to the jacket 48 on the member 44 to an elbowed line 71 connected to the outlets 42 and 49 and the jacket 48 connected to the jacket 37 on the lower container through a similar line 72 connected to the outlets 51 and 41. A suitable heating medium, such as oil, is preferably charged through the inlet 43 so that it will circulate about the upper container, the member 44 and the lower container, and out of 40 the outlet 39 to heat the contents of the apparatus.

45 A pipe 73 having a tapered mouth 74 is positioned in the upper container, having an elbow extending through a packing gland 75 in the wall of the container. It is intended that the pipe be rotated in the gland to draw off liquids from different levels within the container, a valve and rotating means (not shown) being provided on the outside. The bowl shaped plate 50 46 is provided with an aperture 76 in which is connected a pressure inlet line 77, which forces material in the lower container out of the conduit 53. A valve 78 is interposed in the line 55 77 to control the admission of the agent employed, which is preferably air.

60 This apparatus may be provided with the usual temperature and pressure indicating means, such as a thermometer and a pressure gauge, as well as a pressure control valve of conventional type. It may also be desirable to provide a well with a sight glass therein as shown in Fig. 1 of application No. 373,674, of which this application is a division, to allow 65 observation of the liquid levels therein when it is desired to draw off a certain quantity of liquid through pipe 73.

70 This apparatus is suitable for hexachlorethane although it is of course, as previously explained, susceptible for use with a number of similar materials as well, such as naphthalene, borneol, anthracene, or any volatile solid having a low intersolubility with a contained liquid at or above the melting point of the solid, from which it is desired to remove contained liquids. In

treating hexachlorethane, for example, the valve is opened, that is, the plug 63 is positioned as shown in Fig. 1, the cover 68 is removed, and the hexachlorethane charged through the opening formed by the tubular extension 66.

80 The material passes on down through the aperture 47 into the lower container. The charging is continued until the lower container is filled, and hexachlorethane added until the upper container is preferably three-fourths filled, after which the addition of hexachlor- 85 ethane is discontinued and the cover replaced and made tight.

90 Oil or any other suitable heating medium is then introduced, as previously explained, into the jackets surrounding the containers until the hexachlorethane is melted and the water separated in a distinct line.

95 Liquefaction of the hexachlorethane will occur at around 184° C. and a pressure of approximately 160 pounds per square inch generated. The temperature and pressure may be observed by a suitable thermometer and pressure gauge. The temperature may be controlled by regulation of the liquid circulating through the 100 heating jackets. It has been found that both the pressure and temperature will vary somewhat within certain limits according to the amount of impurities present.

105 In this state, the water layer is then removed through the pipe 73, the same either being rotated slowly toward, or positioned at the interface between the layers, the flow being controlled by a valve outside the container (not shown). After the major portion of the water 110 has been removed, communication between the containers is stopped by manipulation of the hand wheel 65, seating the plug 63 in the aperture 47.

115 The contents of the chamber 35 may then be allowed to cool to around 185° C. when they may be blown through the conduit 53 by the introduction of air or other pressure medium through line 77, air preferably being admitted at about 175 pounds per square inch gauge pressure.

120 A line 79 having a valve 81 interposed therein is connected with the conduit 53 adapted to convey the material from the lower container to a cooling chamber 82 where the hexachlor- 125 ethane may be subsequently obtained substantially free from moisture. When it is desired to remove the material from the container, such removal may be controlled by the valve 78.

130 After the charge has been blown from the chamber, the valve 78 is then closed and more heat applied to the charge in the upper chamber, making certain that the hexachlorethane is at least one to two degrees centigrade above its melting point. Communication is then re-established by removal of the plug 63 from the 135 aperture 47, further introduction of air through the line 77 being discontinued, permitting the molten hexachlorethane remaining in the upper chamber to pass into the lower chamber together with any small amount of water it may contain, preliminary to repeating the entire process.

140 There is accomplished by this invention a process and apparatus for removing contained liquids from volatile solvents having a low inter- 145 solubility therewith in the liquid phase without any appreciable loss of the normally solid material, and more especially a process and apparatus for drying hexachlorethane without loss of any substantial quantity of the compound. 150

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

10 I claim:

1. A process of separating a contained liquid and a solid without loss of the solid by vaporization, the solid having a high vapor pressure at room temperature and having a low intersolubility therewith and a different specific gravity from that of the liquid comprising heating within a closed space until the solid is liquefied and the liquefied solid and liquid separate due to their different specific gravities, and then withdrawing one of the separated products.

2. A process of removing contained liquid from a volatile solid without loss of the solid by vaporization, the solid having a high vapor pressure at room temperature and, the solid having a different specific gravity from that of the liquid, comprising liquefying the solid by heat in a closed space, and then withdrawing the liquid.

3. A process of removing a contained liquid from a solid without loss of the solid by vaporization, the solid having a high vapor pressure at room temperature and having a low intersolubility therewith in the liquid phase comprising heating the solid above its melting point in a closed space, and drawing off one of the separated products.

4. A process of drying volatile water-containing solids without loss of the solid by vaporization, the solid having a high vapor pressure at room temperature and having a low intersolubility with water in the liquid phase comprising heating the solid above its melting point in a closed space, and drawing off the water.

5. A process of drying hexachlorethane comprising heating the hexachlorethane in a closed space until it is liquefied, and withdrawing one of the separated products.

6. A process of drying hexachlorethane comprising heating the hexachlorethane in a closed space until it is liquefied, and withdrawing the water.

7. A process of removing contained liquids from solids without loss of the solid by vaporization, the solid having a high vapor pressure at room temperature and having a low intersolubility therewith comprising heating the solid in a closed space, until it liquefies, thus causing a separation into layers of the liquid and the liquefied solid, and drawing off the normally solid while in its liquid phase.

8. A process of separating a contained liquid from hexachlorethane comprising heating the hexachlorethane in a closed space until it liquefies, thus causing a separation into layers of the hexachlorethane and the liquid to be separated from the hexachlorethane, and then drawing off the liquefied hexachlorethane.

9. A process of separating a contained liquid and a solid without loss of the solid by vaporization, the solid having a high vapor pressure at room temperature and having a low intersolu-

bility therewith and a different specific gravity from the liquid comprising heating the solid above its melting point in a plurality of superimposed communicating spaces, stopping communication between said spaces, and withdrawing the separated products.

10. A process of separating a contained liquid and a solid without loss of the solid by vaporization, the solid having a high vapor pressure at room temperature and, the contained liquid having a different specific gravity from the solid, comprising heating the solid above its melting point in a plurality of superimposed communicating spaces, stopping communication between said spaces, and removing the solid while in liquid phase.

11. A process of separating a contained liquid and a solid without loss of the solid by vaporization, the solid having a high vapor pressure at room temperature and, the contained liquid having a low intersolubility with and a different specific gravity from that of the solid when the solid is in its liquid phase, comprising heating the solid in a closed space, until the normally solid material is in its liquid phase, and drawing off the normally solid material while in its liquid phase.

12. A process of separating a contained liquid and a solid without loss of the solid by vaporization, the solid having a high vapor pressure at room temperature and, the contained liquid having a low intersolubility with and a different specific gravity from that of the solid when the solid is in its liquid phase, comprising heating the solid in a closed space until the normally solid material is in its liquid phase, separating the liquid from the liquefied solid, and drawing off the liquefied solid.

13. A process of separating a contained liquid and a solid without loss of the solid by vaporization, the solid having a high vapor pressure at room temperature and, the contained liquid having a low intersolubility with and a different specific gravity from that of the solid when the solid is liquefied, which comprises heating the solid in a closed space until the solid material is liquefied drawing off most of the liquid, separating the liquefied solid from the remaining liquid, and drawing off the liquefied solid.

14. A process of separating a contained liquid and a solid without loss of the solid by vaporization, the solid having a high vapor pressure at room temperature and, the contained liquid having a low intersolubility with and a different specific gravity from that of the solid when the solid is liquefied, which comprises heating the solid in a closed space until the solid is liquefied, drawing off most of the liquid, separating the liquefied solid from the remaining liquid, and putting pressure on the liquefied solid and blowing it out of the closed space.

15. A process of drying hexachlorethane comprising heating the same above its melting point within two superimposed communicating spaces, stopping communication between said spaces, withdrawing the hexachlorethane from the lower space, and removing the water layer upon the hexachlorethane in the upper space.

ROLLAND D. MYERS. 145
